ADOLF FRITZ SCHAUSS, OF OBERURSEL, NEAR FRANKFORT-ON-THE-MAIN, GERMANY

TYPEWRITER

Application filed April 25, 1927, Serial No. 186,408, and in Germany November 30, 1926.

This invention relates to an improvement effected in the small typewriter according to U. S. Pat. Appl. Ser. No. 70,490 with a typebar rest located immediately and vertically in front of the paper cylinder. With known machines the considerable lengths of typebars are prejudicial to the touch. It has therefore been proposed to build small typewriters having the typebar rests vertically arranged in front of the paper cylinder, and continuous key-levers. But owing to the restricted length available in the construction of the machine, the key-levers are proportioned very short from their pivotal points to the key-heads and on account of the necessity for depression of the key-levers the key-heads, as regards the pivoting points of the levers, are located very high and mounted upon long key-rods; the latter of necessity therefore tend to bend forward considerably on being depressed. This is especially the case with the top row of keys, which swing out in an arc with the distance to the pivotal connection to the key-lever as radius.

This considerable outward movement and slipping of the keys beneath the fingers of the typist is found to be very unpleasant and becomes very tiring with continuous typing.

The principal U. S. Pat. Appl. Ser. No. 70,490 proposed to obviate this disadvantage of the continuous key-levers and to replace the latter by key-rods guided through slots in a guide-plate, the key-rods being coupled to angle-levers, which transmit motion by means of coupling levers, the latter being connected with the typebars on the one hand and with the angle-levers on the other by means of jointed connecting rods.

By this arrangement a system of drive levers was obtained, which was composed of many parts and was sensitive and costly. The invention obviates these disadvantages without sacrificing the vertical arrangement of the typebar rest, and without increasing the dimensions of the machine.

The solution is found by a new and special arrangement of the key and typebar system and a more suitable location of its parts.

To obtain a smaller height of the machine from the base to the middle of the paper cylinder the typebars are of smaller proportions than with usual typewriters.

In the drawings a constructional form of the invention is shown by way of example, and illustrates a machine according to the principal U. S. Pat. Appl. Ser. No. 70,490, in which for greater clearness the parts which here are not necessary, have been omitted.

Fig. 1 shows diagrammatically the arrangement of the new key and typebar system in longitudinal section through the middle of a machine and shows a typebar in the striking position in dotted lines.

Fig. 2 shows in detail the arrangement of one of the outside type-levers together with its coupling lever.

Fig. 3 shows on the left half a section through the typebars with a view of the segment for the coupling levers and typebars, the right half shows a view of the cushion for the typebars with the typebar segment behind, and simultaneously a section through the coupling lever segment with the raised shank of the coupling lever.

Fig. 4 is a diagrammatic plan from above of the angle-lever with its segment and spring mechanism.

The frame casing *a* of the machine may be made and arranged in the manner already set forth in the principal U. S. Pat. Appl. Ser. No. 70,490. Upon the back wall is guided the carriage *b*, which rests upon the angle frame *c*. The key-heads are marked *d* and the return rod for release of the control and speedy return of the typebar to its cushion is marked *e*.

In front of the paper cylinder is located vertically the typebar segment *f*, in which the typebars *g* are mounted upon a common spindle *h*. Each typebar *g* rests in inoperative position with its head upon a cushion *i*. Beneath the typebar segment *f* a coupling member *k* is located and attached radially to the middle point of the typebar segment. The coupling levers *m* mounted upon a common pivot rod *l* each engage by means of lateral pin *m*¹ in a slot *g*¹ of their particular

typebars g . This slot g^1 terminates in a curved end g^2 of special formation.

In order, in spite of the great number of typebars and their short length and also the small proportions of the typebar segment, to obtain enough space for the type upon the cushion of the supporting hoop without making the distance of the outer segment slots and the angle taken up by the typebars much larger than with large office machines, the outermost typebars are spaced further apart or bent laterally in the position of rest with relation to the more central typebars. The outermost typebars thus traverse upon the way from the cushion i to the striking position on the paper cylinder a longer path than the inner ones. Also the coupling-levers m located in a circle round the typebars are proportioned considerably smaller between their pivotal points and the points of engagement in the slots g^1 of the typebars than similarly arranged coupling levers of the larger machines. On account of the greater spacing between the outer typebars g , and of the small length of the coupling levers m a different angle of the coupling levers m in the slot g^1 of the typebars arises with the outer typebars. This continually decreasing angle towards the outer typebars influences, however, compared with the central typebars, the rapidity of action of the said outer typebars, and also the strength of the touch on the keys and the depression of the keys. In order to overcome this disadvantage, that is to say, so as to keep the angular relation of the coupling levers m to their engaging surfaces in the slots of the typebars approximately in the same angle radius, the ends of the slots are curved in a special manner.

Figs. 1 and 2 will explain this. The first figure shows the position of engagement of the coupling lever with a central typebar; the detail figure according to Fig. 2 shows the position of the coupling lever at the point of engagement for an outer typebar.

It is easily seen from these two figures, how the angular position of the typebar slot g^1 to the pivotal point of the typebar changes with the outer typebar, which is placed further over, and accordingly the angular position of the coupling lever m in the slot of the typebar is different also.

In Fig. 1 the angle between the working slot g^1 of the typebar and the middle line of the coupling lever is marked alpha, and in Fig. 2 beta. With the outermost typebar shown in Fig. 2 the coupling lever is placed further back, since it has the same length as that in the middle of Fig. 1 and the angular position of the slots is the same with all 44 typebars. With no curved construction of the typebar slot the angle beta would become very much smaller in relation to the angle alpha of the middle lever. The en-

gaging surface of the guiding pin m^1 of the coupling lever m in the slot g^1 would be too flat and it would cause the above-mentioned disadvantages. The curve of the typebar slot is therefore so made, that the angle of engagement of the coupling lever in the slot of the typebar remains the same or approximately the same with all type bars.

The machine is of very small dimensions, not only in height but also in length. The first row of keys is arranged as near as possible to the cushion i for the typebars. Since the limited space makes the employment of continuous key-levers, as commonly used with large machines, impossible, a key-lever in several parts is provided, consisting of a key-rod and an angle-lever, the latter being connected to the coupling lever by means of a rod. The key-rod r , which passes through the slot in a guide-plate s , is connected at its lower end with an angle-lever o , which is so arranged beneath the space occupied by the typebars when inoperative, that its pivotal point or pivotal axis does not lie lower than the pivoted point of the most central of the coupling levers m , arranged in an arc beneath the typebars g and the height of the machine from the bottom to the centre of the paper cylinder is not greater than that entailed by the length of the typebars and the coupling levers. In order not to increase the height of the machine thus established owing to the forward movement of the extensions coupled to the key-rods when the keys are depressed, the angular positions of the front extensions o^1 , are again so arranged, that the latter on depression do not descend beyond the deepest point of their pivotal axes n^1 . Since this extension of the angle lever does not turn about its own middle pivotal point and also, particularly with the first row of keys, takes up a considerably acute angular position upwards, it moves forwards through a large arc. The angle-levers o for all the rows of keys are arranged upon a spindle n^1 . The front extension of the second, third and fourth row of keys is each successively longer than the former on account of the distance from one row of keys to the next row of keys, and therefore the outward movement of the angle-levers, the ends of which should lie at the same height, becomes less. The key-rods r pivotally mounted upon the ends of these angle-levers o are guided in slots in a stepped guide-plate s . With the longest key-lever the stepped plate is at its lowest and with the shortest at its highest. By these means the key-rods are so guided, that the depression of the key-heads is almost the same and is substantially regular for all four rows. The unfavourable forward movement of the key-heads, usual with other ma-

chines, and especially with those of small dimensions, is thus completely obviated.

Beneath the typebar cushion *i* the angle-lever segment *n* is arranged. All the angle-levers *o* for all four rows of keys are mounted upon the spindle *n*¹. The levers *o* are pressed with their front extensions against the striking cushion *q*, by means of springs *p*, which are secured on the one hand to the noses *o*³ of the levers and on the other to the noses *n*³ stamped out of the sheet metal forming the angle-lever segment.

The key-rods *r* are connected to the angle-lever extensions *o*¹. The former pass, as already described, through apertures in a guide-plate *s* formed in steps. Since the longest extension *o*¹ of the angle-lever engages with the shortest rod *r* and the shortest extension *o*¹ with the longest rod *r*, and the relation of the steps of the guide-plate for the key-rods to the length of the angle-lever extension *o*¹ is approximately proportional, the key-heads describe an almost perpendicular path downwards and the scarcely perceptible forward movement is the same for all.

Fig. 3 shows on the right hand a section through the angle-lever segment *n* looking on the raised extension *o*² of the angle-lever. As will be seen, the extensions of the outer angle-levers are longer than those of the inner ones. The result is thus secured, that the direction of pull of the connecting rods *t* from the coupling levers to the angle-levers is not too oblique or slanting on account of the short distance between the angle-lever segment and the coupling lever segment.

The much altered conditions of connection and transmission for the several systems are again compensated by means of the displacement of the point of engagement of the rod *t* with the coupling lever *m*. The length of the rod *t* is rendered adjustable by the insertion of a threaded coupling. Since the forces, which arise on driving the coupling lever by means of pressing down the key-head, work in opposite directions to one another for the coupling and angle-lever segments (see the arrows in Fig. 1) the two segments are stiffened in the middle of the machine by a stay *u*.

I claim:—

1. A typewriter having in combination on a frame, a slidable carriage and roller in the rear part of the said frame, a key board with rows of keys and corresponding key rods at the front of said frame, the length of the key rods decreasing in length from row to row towards the front of the frame, a stepped guide plate for the key rods, pivoted typebars adapted to swing upward for printing and arranged in a circular, substantially vertical sector, coupled levers pivotally mounted in a segment lying con-

centrically to the typebar sector, coupling means between the typebars and the coupling levers, angle levers pivotally arranged on a common spindle and comprising substantially forwardly directed extensions of different lengths and substantially upwardly directed extensions of different heights, the shortest of said forwardly directed extensions being connected to the longest of the said key rods and progressively the longest of such extensions being connected to the shortest of the key rods and connecting rods connecting said upwardly directed extensions to the said coupling levers.

2. In a typewriter in connection with a key board with rows of stepped key rods, angle levers pivotally arranged on a common spindle and comprising substantially forwardly directed extensions of different lengths and substantially upwardly directed extensions of different heights, the shortest of said forwardly directed extensions being connected to the longest of the said stepped key rods and progressively the longest of said extensions being connected to the shortest of the said stepped key rods, connecting rods connected at one end to the said upwardly directed extensions of the said angle levers, coupling levers connected to the other ends of said connecting rods, pivoted type bars adapted to be swung upward for printing, curved slots in said type bars and pins on said coupling levers engaging said slots, the different heights of the said upwardly directed extensions of the angle levers being compensated by a corresponding displacement of the connecting points between the connecting rods and the coupling levers.

3. In a typewriter in connection with a key board with rows of key rods, spring actuated angle levers pivotally connected at one end to the said key rods, a striking cushion for the same, connecting rods connected with one end to the other end of said angle levers, coupling levers connected to the other end of said connecting rods, pivoted typebars adapted to be swung upward for printing and arranged in a circular substantially vertical sector, the outer typebars being spaced further apart, slots in the lower ends of said type bars and pins on the adjacent ends of the coupling levers engaging said slots, the ends of the said slots being curved to compensate the altered angular position of the coupling lever to the typebars in the outer typebars which are spaced further apart.

4. In a typewriter a printing mechanism comprising pivoted typebars adapted to be swung upward for printing, coupling levers, operatively connected thereto and being pivotally arranged on a common spindle, a coupling lever segment, a key board with rows of key rods, spring actuated angle levers pivotally connected to the key rods,

a common spindle and a segment for the angle levers, connecting rods between the coupling levers and the angle levers and a stay between the coupling lever segment and the angle lever segment.

5. In a typewriter a printing mechanism comprising pivoted typebars adapted to be swung upward for printing, coupling levers operatively connected thereto and being pivotally arranged on a common spindle, a coupling lever segment, a key board with rows of key rods, spring actuated angle levers pivotally connected to the key rods, a common spindle and a segment for the angle levers, connecting rods between the coupling levers and the angle levers and a stay between the coupling lever segment and the angle lever segment which stay comprises two parts which are connected by screws in such a manner that the length of the stay can be regulated.

In testimony whereof I affix my signature.
ADOLF FRITZ SCHAUSS.
